UNITED STATES PATENT OFFICE.

SIMON YASULAITIS, OF BROOKLYN, NEW YORK.

LIFE-BOAT.

1,277,522.

Specification of Letters Patent. Patented Sept. 3, 1918.

Application filed October 31, 1917. Serial No. 199,472.

To all whom it may concern:

Be it known that I, SIMON YASULAITIS, a citizen of Russia, residing at Brooklyn, in the county of Kings, State of New York, have invented certain new and useful Improvements in Life-Boats; and I do hereby declare the following to be a full, clear, and exact description of the invention, such as will enable others skilled in the art to which it appertains to make and use the same.

This invention relates to improvements in life boats.

One object of the present invention is to provide a life boat of novel construction which is strong and durable and which will stand rough usage in the sea.

Another object is to provide an improved construction of life boat which will be perfectly sea worthy and which will not be liable to leak.

A further object is to provide an improved life boat which will be practically puncture-proof and which will be practically indestructible.

25 A further object is to provide a life boat having a novel and efficient and improved means for launching the same from a ship, whereby the loosening, by hand, of davit ropes, or other lines, is obviated, the release 30 of the boat being automatic as soon as it touches the water and floats.

Other objects and advantages will be apparent from the following description when taken in connection with the accompanying 35 drawing.

In the drawings:

Figure 1 is a side elevation of a life boat made in accordance with my invention, the cover or roof being in elevated or closed 40 position.

Fig. 2 is a top plan view of the boat with the cover or roof in lowered or open position.

Fig. 3 is an enlarged sectional perspective 45 view of a portion of the wall of the boat, the different layers of the wall being spread apart.

Fig. 4 is an enlarged perspective view of one of the steel bracing members.

50 Fig. 5 is a vertical transverse sectional view taken on the line 5—5 of Fig. 1.

Fig. 6 is an enlarged elevation of one of the port lights, viewed from the interior of the boat.

Referring particularly to the accompanying drawings, there is shown a life boat made in accordance with my invention.

The walls of the boat are formed from a plurality of layers of different materials, which will now be described and particularly referred to by reference numerals.

The innermost layer 10 is formed from a waterproof fabric. Next, outwardly of this layer 10 is a layer of closely woven wire screen 11, and outwardly of this screen is a second layer of screen cloth 12. Between these layers of screen there is disposed the spring steel bracing members, shown in detail in Fig. 4. These bracing members each include longitudinal strips of spring steel 13 which extend from one end of the boat to the other, and at the sides thereof. Disposed transversely of the steel strips 13, and secured thereto at their intermediate portions, are the shorter strips of steel 14. Also secured to the strips 13 and 14, and extending longitudinally thereof, are the shorter strips 15, further strips 16 being secured to the strips 14 and 15. Cross strips 16' are secured at the points where the strips 15 are joined to the strips 13.

Outwardly of the screen 12 there is disposed a layer of waterproof cloth 17, such as rubberized fabric. Next outwardly of the layer 17 are two layers of canvas 18 and 19, and next outwardly of these layers is a layer of rubber and fabric 20, similar in construction to the outer shoe of an automobile tire. Outwardly of the layer 20 is a layer of canvas 21. Outwardly of the layer 21 is a layer of closely woven wire screen cloth 22 and outwardly of this screen, and forming the outermost layer or surface of the body of the boat, is a layer of heavy wire rope or cable woven into the form of a net, as shown at 23.

The spring steel braces, together with the layers of the woven wire screen, serve to hold the boat in proper shape, and also prevent any breakage or puncturing. The sides of the boat will be resilient and thus resist any tendency toward crushing when in rough seas or when striking reefs or other submerged objects.

The keel 24 consists of a length of heavy wire cable or rope, while slightly smaller wire ropes or cables 25 form the gunwales of the boat.

Thus there is provided a simple and practically indestructible boat, and one which is comparatively light in weight.

To the gunwales of the boat are secured the 5 longitudinally extending metal strips 26, and connected to these strips are the sheets of waterproof fabric 27. A pair of longitudinally extending and outwardly bowed metal strips 28 are pivotally connected to 10 together at their ends and to the connected ends of the strips 26, as shown at 29. These strips 28 are adapted to be swung into position on the gunwales of the boat at times, and into overlapping relations above the boat 15 at times. The remaining marginal edges of the sheets 27 are secured to these bowed strips 28, and together with said strips, form a cover or roof, which, when raised, as shown in Figs. 1 and 5, will protect the occupants 20 of the boat in inclement weather.

In each of the fabric sheets are secured the porthole frames 30 and the vertical ventilating tubes 31, said tubes having the caps or hoods on their upper ends to prevent the entrance of water. A door 32 is hinged to 25 each of the frames 30 to close the opening therethrough, and is formed with a bifurcated extension 33 for the reception of the turn-button 34 carried by the adjacent side 30 of the frame.

Extending rearwardly from the stern of the boat, at the level of the gunwales, is a frame 35 to the outer end of which is connected the upturned end portion of an L-shaped member which is secured to the keel, 35 as shown at 36. Within this frame, and secured to the stern of the boat, is a vertical frame 37 in which is mounted a vertical shaft 38 carrying a rudder blade on the lower end, 40 as at 39, the lower end of said shaft being journaled in the horizontal portion of the L-shaped member 36. Mounted in the upper and lower portions of the vertical frame are the shafts 40 and 41, the upper one having a 45 sprocket wheel 42, while the lower one carries a sprocket wheel 43 and a propeller 44. A drive chain 45 is engaged around these sprocket wheels, as clearly shown. Secured to the inner end of the rear of the boat is a 50 transversely disposed and vertically arranged plate 46 and through this plate extends the inner-end portion of the upper shaft 40, said inner end of the shaft being provided with a crank handle 47 for rotat- 55 ing the shaft 40 with the transmission of power to the propeller to drive the boat. Formed on the plate 46 is a horizontal por-

tion 48 and rotatably mounted on this portion is a wheel 49 which is connected to the rudder shaft by means of the cords 50.

Mounted on the bow of the boat, as well as on the stern thereof, is an outwardly extending bracket 51. Pivotally mounted on each of these brackets is a vertically disposed hook member 52, said member being normally urged toward the boat by a spring 53. The hook member is arranged to be moved outwardly and engaged with a ring 54 carried by the lower end of one of the davit ropes 55. When the boat is lowered to the water, and floats, the said ropes and rings will naturally sag downwardly and out of engagement with the hooks, thereby permitting the springs to draw the hooks inwardly toward the boat and completely out of the way. When the hooks are engaged with the rings of the davit ropes the weight of the boat will hold them in such position against the springs 53. Thus the usual method of casting off lines when a boat is 80 launched from a ship, or detaching hooks or ropes from the davits, is entirely obviated.

From the foregoing it will be seen that I have provided a novel and simple as well as durable life boat, and one which is easily 85 and quickly launched from a ship, even in a rough sea. Furthermore, it will be seen that the boat is capable of properly protecting the occupants from the weather, while at the same time means are provided whereby 90 the occupants can propel the boat and steer the same, as desired.

Furthermore, the construction of the hull of the boat is such that danger of leakage or crushing thereof is unlikely, as the sides of 95 the hull are possessed of such elasticity that bending or denting is as far as the damage will go.

What is claimed is:

A boat construction consisting of layers of 100 waterproof fabric, layers of woven wire screen stiffening means, layers of waxed and oiled fabric, spring metal bracing members disposed between certain of the layers, and an outer shell of woven metal netting, the 105 keel and gunwales of the boat being formed from lengths of metal cable.

In testimony whereof, I affix my signature in the presence of two witnesses.

SIMON YASULAITIS.
